UNITED STATES PATENT OFFICE.

MARCUS M. BEEMAN, OF MEADVILLE, PENNSYLVANIA, ASSIGNOR TO THE SPIRELLA COMPANY, OF MEADVILLE, PENNSYLVANIA, A CORPORATION OF PENNSYLVANIA.

GARMENT-STAY.

1,098,468.

Specification of Letters Patent.

Patented June 2, 1914.

Application filed December 5, 1908. Serial No. 466,148.

To all whom it may concern:

Be it known that I, MARCUS M. BEEMAN, a resident of Meadville, in the county of Crawford and State of Pennsylvania, have 5 invented a new and useful Improvement in Garment-Stays, of which the following is a specification.

This invention relates to stays for garments and the like, and more particularly 10 to stays for corsets.

The object of the invention is to provide a stay for this purpose which will readily yield edgewise as well as sidewise, which is highly elastic and in which the bending is 15 not concentrated at any point or points so as to avoid crystallization and breakage.

A further object is to provide a stay of the character named which can be readily and cheaply manufactured.

20 The invention comprises the stay herein-after described and claimed.

In the accompanying drawing Figure 1 is a face view of the stay; Fig. 2 is a face view of the blank before the final bend; Fig. 25 3 is a perspective view illustrating the final bending of the stay; Fig. 4 is a cross section through the stay; Fig. 5 is a face view of a modification employing two wires instead of a single wire; and Fig. 6 is a face 30 view of the blank for the latter before the final bending.

The stay shown in Figs. 1 to 4 is formed from a single continuous wire 1, which is bent back and forth to form a series of 35 oppositely disposed loops or eyes 2, each of which normally partly overlaps the side of an adjoining loop or eye, as at 3, and the transverse portions of the wire, or crossings 5 lying at a slight angle from the normal to 40 the longitudinal axis of the structure. This gives each side of a loop or eye a bearing upon the side of an adjoining loop or eye and all of the said loops or eyes are flat.

The overlapping of these loops or eyes upon 45 each other permits them to slide one on the other when the stay is bent in any direction, forward, back or sidewise, and absolutely prevents any short bends or concentration 50 of bending at a point or few points and prevents breakage or destruction of the resiliency of the spring. By having the eyes or loops bear one on the other when the stay is flexed the strength of the stay is greatly increased and the bending stresses exerted on 55 any one loop or eye are on this bearing trans-

ferred in part to the adjacent eye or eyes. The blank so formed is completed by bending it on the central longitudinal line, as shown in Figs. 3 and 4, that is, folding one-half the blank over onto the other. The stay so formed is therefore composed of two series of loops or eyes one superimposed on the other with the closed end portions of the loops forming one edge of the stay while the opposite edge is formed by the intermediate joining portion 5. The loops or eyes shown in the drawings are of pear-shape, that is being wide and round at their closed ends and gradually tapering toward their open ends, but the shape may be changed as 70 desired.

Figs. 5 and 6 show a modification in which the stay is composed of two wires 6 and 7 each formed into a series of loops substantially pear-shape, alternate ones of the loops 75 or eyes being formed in one wire and the intermediate ones being formed in the other wire. The ends of the stay are finished by applying a suitable metal clip thereto and the stays will be inclosed in the usual casting 80 which usually forms a part of the fabric of the corset or other garment.

The stay described has its loops or eyes lying in two superimposed planes with the loops or eyes in each plane partly overlapping and bearing against the loops or eyes on each side so as to transfer strains from one loop to the other. This stay is flexible 85 in all directions, edgewise as well as sidewise, and the bending is not confined at any one point or few points, thus avoiding crystallization and breakage. The overlapping 90 of the loops gives suitable rigidity so that light wire can be used, and also increases the elasticity so that the stay does not take 95 a permanent set.

What I claim is:—

1. A garment stay comprising a flat wire structure having a series of overlapping loops or convolutions, said wire structure 100 being folded longitudinally upon itself to form a plurality of superimposed plies in parallel planes, said plies being connected to each other only along the line of fold, so that the wire structures of the different plies 105 act independently of each other on either edgewise or flatwise flexure of the stay.

2. A device for use as a corset stay comprising a flat structure of wire bent into 110 sinuous or serpentine form with successive

loops or convolutions and connecting crossings, said wire structure being folded longitudinally upon itself along its median line to form a plurality of superimposed plies in 5 parallel planes, said plies being connected to each other only along one edge of the stay at the line of fold, whereby the wire structures of the different plies act independently

of each other on either edgewise or flatwise flexure of the stay. 10

In testimony whereof, I have hereunto set my hand.

MARCUS M. BEEMAN.
